(57) **ABSTRACT**

A motor-driven compressor, a housing structure for a motor-driven compressor, and a method of installing a soundproof cover on a motor-driven compressor are provided. A soundproof cover includes layers that include a first layer and a second layer. The first layer is placed over a housing, and the second layer is placed over the first layer. Each of the layers includes a first segment and a second segment. A second selection layer is located inward of a first selection layer. A boundary in the second selection layer is located above the boundary of the first selection layer.

**MOTOR-DRIVEN COMPRESSOR, HOUSING
STRUCTURE FOR MOTOR-DRIVEN
COMPRESSOR, AND METHOD OF
INSTALLING SOUNDPROOF COVER ON
MOTOR-DRIVEN COMPRESSOR**

BACKGROUND

1. Field

The present disclosure relates to a motor-driven compressor, a housing structure for a motor-driven compressor, and a method of installing a soundproof cover on a motor-driven compressor.

2. Description of Related Art

A motor-driven compressor includes a compression unit, an electric motor, and a housing. The compression unit compresses a fluid. The electric motor drives the compression unit. The housing accommodates the compression unit and the electric motor.

For the purpose of reducing noise of a motor-driven compressor, the housing of the motor-driven compressor may be covered with, for example, a soundproof shell described in Japanese Laid-Open Patent Publication No. 2013-194673. The soundproof shell includes an upper segment and a lower segment. The upper segment covers an upper part of the housing. The lower segment covers a lower part of the housing.

The upper segment and the lower segment each include a sound absorbing layer and a sound insulating layer. The sound absorbing layer is placed over the housing. The sound insulating layer is placed over the sound absorbing layer. The upper segment and the lower segment abut each other to cover the housing. The soundproof shell is formed by multiple layers including the sound absorbing layers and the sound insulating layers.

SUMMARY

This Summary is provided to introduce a selection of concepts in a simplified form that are further described below in the Detailed Description. This Summary is not intended to identify key features or essential features of the claimed subject matter, nor is it intended to be used as an aid in determining the scope of the claimed subject matter.

In a first general aspect, a motor-driven compressor includes a compression unit that compresses a fluid, an electric motor that drives the compression unit, a housing that accommodates the compression unit and the electric motor, and a soundproof cover that covers the housing. The soundproof cover includes layers that include a first layer and a second layer. The first layer is placed over the housing, and the second layer is placed over the first layer. Each of the layers includes a first segment and a second segment. Each first segment is located above a boundary between the first segment and the corresponding second segment. Each second segment is located below the corresponding boundary. One of the layers is defined as a first selection layer. Another one of the layers that is located inward of the first selection layer is defined as a second selection layer. The boundary in the second selection layer is located above the boundary of the first selection layer.

With the above-described configuration, the boundaries in the multiple layers forming the soundproof cover include boundaries that are displaced from each other in the up-

2

down direction. In other words, the boundaries in all the layers do not extend continuously from the housing to the outside of the soundproof cover. Thus, the noise generated by the compression unit and the electric motor is unlikely to leak to the outside of the soundproof cover. Therefore, the noise reduction effect of the soundproof cover is unlikely to be reduced.

Further, the boundary in the second selection layer is located above the boundary of the first selection layer. For 10 this reason, even if water enters the boundary in the outermost layer located at the outermost position among all the layers to reach the boundary in the first selection layer, the water is unlikely to reach the boundary in the second selection layer. Thus, even if water enters the motor-driven 15 compressor from the outside, the water is unlikely to reach the housing. Therefore, it is possible to maintain the noise reduction effect of the soundproof cover while preventing water from reaching the housing.

If the boundary between the sound absorbing layer of the 20 upper segment and the sound absorbing layer of the lower segment and the boundary between the sound insulating layer of the upper segment and the sound insulating layer of the lower segment are located at the same position in the up-down direction, water may enter the housing from the 25 outside of the soundproof shell through the boundaries. In addition, although the soundproof shell reduces the noise of the motor-driven compressor, the noise reduction effect may be reduced if all the boundaries are located at the same 30 position in the up-down direction. The above-described configuration prevents such possible disadvantages.

In the above-described motor-driven compressor, the boundary in an outermost layer, which is located at an outermost position among the layers, is preferably located at a lowermost position among the boundaries in the layers.

With the above-described configuration, water entering the boundary in the outermost layer is unlikely to pass through the boundaries in the layers on the inner side of the outermost layer. Therefore, water is unlikely to reach the housing.

40 In a second general aspect, a housing structure for a motor-driven compressor includes a cylindrical housing and a cylindrical soundproof cover that covers the housing. The soundproof cover includes layers that include a first selection layer and a second selection layer. The second selection 45 layer is located inward of the first selection layer. Each of the layers includes a first segment and a second segment that is located below the first segment. A length of the first segment of the first selection layer in a circumferential direction is greater than a length of the first segment of the second selection layer in a circumferential direction.

45 In a third general aspect, a method of installing a soundproof cover on a motor-driven compressor includes providing first segments and second segments. Each of the first segments and each of the second segments form corresponding 50 one of layers that form the soundproof cover. The soundproof cover covers a housing of the motor-driven compressor. The layers include a first layer and a second layer. The first layer is placed over the housing, and the second layer is placed over the first layer. Each first segment is located above a boundary between the first segment and the corresponding second segment. Each second segment is located below the corresponding boundary. One of the layers is defined as a first selection layer. Another one of the layers that is located inward of the first selection layer is defined as a second selection layer. The boundary in the second selection layer is located above the boundary of the first selection layer. The method also includes forming a first intermediate

by stacking the first segments of the layers together, forming a second intermediate by stacking the second segments of the layers together, and covering the housing with the first intermediate and the second intermediate by joining the first intermediate and the second intermediate to each other.

With the above-described installing method, the first segments of the multiple layers are stacked together in advance to form the first intermediate. Also, the second segments of the multiple layers are stacked together in advance to form the second intermediate. This configuration simplifies the final step of attaching the soundproof cover to the housing of the motor-driven compressor.

In the motor-driven compressor on which the soundproof cover is installed by the above-described installing method, the boundaries in the multiple layers forming the soundproof cover include boundaries that are displaced from each other in the up-down direction. In other words, the boundaries in all the layers do not extend continuously from the housing to the outside of the soundproof cover. Thus, the noise generated by the compression unit and the electric motor is unlikely to leak to the outside of the soundproof cover. Therefore, the noise reduction effect of the soundproof cover is unlikely to be reduced.

Further, the boundary in the second selection layer is located above the boundary of the first selection layer. For this reason, even if water enters the boundary in the outermost layer located at the outermost position among all the layers to reach the boundary in the first selection layer, the water is unlikely to reach the boundary in the second selection layer. Thus, even if water enters the motor-driven compressor from the outside, the water is unlikely to reach the housing. Therefore, it is possible to maintain the noise reduction effect of the soundproof cover while preventing water from reaching the housing.

The present disclosure maintains the noise reduction effect of the soundproof cover, while preventing water from reaching the housing.

Other features and aspects will be apparent from the following detailed description, the drawings, and the claims.

BRIEF DESCRIPTION OF THE DRAWINGS

FIG. 1 is a cross-sectional view of a motor-driven compressor according to a first embodiment of the present disclosure.

FIG. 2 is a cross-sectional view taken along line 2-2 in FIG. 1, illustrating the motor-driven compressor according to the first embodiment.

FIG. 3 is a cross-sectional view illustrating a method according to the first embodiment for manufacturing the motor-driven compressor shown in FIG. 1.

FIG. 4 is a cross-sectional view of a motor-driven compressor according to a second embodiment of the present disclosure.

FIG. 5 is a cross-sectional view of a motor-driven compressor according to a modification of the present disclosure.

FIG. 6 is a cross-sectional view of a motor-driven compressor according to another modification of the present disclosure.

FIG. 7 is a cross-sectional view of a motor-driven compressor according to a further modification of the present disclosure.

Throughout the drawings and the detailed description, the same reference numerals refer to the same elements. The drawings may not be to scale, and the relative size, propor-

tions, and depiction of elements in the drawings may be exaggerated for clarity, illustration, and convenience.

DETAILED DESCRIPTION

This description provides a comprehensive understanding of the methods, apparatuses, and/or systems described. Modifications and equivalents of the methods, apparatuses, and/or systems described are apparent to one of ordinary skill in the art. Sequences of operations are exemplary, and may be changed as apparent to one of ordinary skill in the art, with the exception of operations necessarily occurring in a certain order. Descriptions of functions and constructions that are well known to one of ordinary skill in the art may be omitted.

Exemplary embodiments may have different forms, and are not limited to the examples described. However, the examples described are thorough and complete, and convey the full scope of the disclosure to one of ordinary skill in the art.

In this specification, "at least one of A and B" should be understood to mean "only A, only B, or both A and B."

A motor-driven compressor 10 according to a first embodiment will now be described with reference to FIGS. 1 to 3. The motor-driven compressor 10 of the present embodiment is used, for example, in a vehicle air conditioner.

<Motor-Driven Compressor>

As shown in FIG. 1, the motor-driven compressor 10 includes a housing 20, a compression unit 30, an electric motor 40, an inverter 50, and a soundproof cover 60. The housing 20 is cylindrical. The housing 20 is made of metal. The housing 20 is made of, for example, aluminum. A direction in which an axis m of the housing 20 extends is defined as an axial direction A. A direction in which a circle around the axis m of the housing 20 extends is defined as a circumferential direction a circumferential direction B. The housing 20 includes multiple housing components separable in the axial direction A.

The compression unit 30 compresses refrigerant, which is fluid. The electric motor 40 drives the compression unit 30. The inverter 50 drives the electric motor 40. The housing 20 accommodates the compression unit 30, the electric motor 40, and the inverter 50. The compression unit 30, the electric motor 40, and the inverter 50 are arranged in that order in the axial direction A of the housing 20.

The electric motor 40 is driven by power supplied from the inverter 50. The compression unit 30 is of a scroll type that includes a fixed scroll and a movable scroll (neither is shown). As the electric motor 40 is driven, the compression unit 30 compresses refrigerant that is drawn into the housing 20.

<Soundproof Cover>

As shown in FIGS. 1 and 2, the soundproof cover 60 covers the housing 20. The soundproof cover 60 includes multiple layers. In the present embodiment, the soundproof cover 60 includes two layers. The two layers are defined as a first layer 70 and a second layer 80. The first layer 70 is placed over the housing 20. The second layer 80 is placed over the first layer 70. The second layer 80 covers the first layer 70. In the present embodiment, the first layer 70 is made of, for example, a urethane material or nonwoven fabric. The first layer 70 is made of a material having high sound absorbing properties. In the present embodiment, the second layer 80 is made of, for example, polypropylene, polyamide, acrylonitrile-butadiene-styrene (ABS) plastic, or

olefin-based elastomer. In the present embodiment, the second layer **80** is made of a material having high sound insulating properties.

The first layer **70** is provided to conform to the outer shape of the housing **20**. The first layer **70** includes a first segment **71** and a second segment **72**. The first segment **71** includes a first accommodating recess **71a**. The first accommodating recess **71a** opens toward the second segment **72**. The second segment **72** includes a second accommodating recess **72a**. The second accommodating recess **72a** opens toward the first segment **71**. The first accommodating recess **71a** and the second accommodating recess **72a** have shapes that conform to the outer shape of the housing **20**.

The first segment **71** includes a first opening end face **71b**. The first opening end face **71b** is an annular flat surface and surrounds the opening of the first accommodating recess **71a**, which faces the second segment **72**. The first opening end face **71b** is a flat surface that extends in the horizontal direction. The second segment **72** includes a second opening end face **72b**. The second opening end face **72b** is an annular flat surface and surrounds the opening of the second accommodating recess **72a**, which faces the first segment **71**. The second opening end face **72b** is a flat surface that extends in the horizontal direction. The term "annular" as used in this description may refer to any structure that forms a loop, or a continuous shape with no ends. "Annular" shapes include but are not limited to a circular shape, an elliptic shape, and a polygonal shape with sharp or rounded corners.

The first opening end face **71b** and the second opening end face **72b** are in contact with each other over the entire periphery. A portion in the first layer **70** at which the first opening end face **71b** and the second opening end face **72b** are in contact with each other is a boundary **73** between the first segment **71** and the second segment **72**. The first segment **71** is disposed above the boundary **73**, that is, at a position corresponding to an upper part of the housing **20**. The second segment **72** is disposed below the boundary **73**, that is, at a position corresponding to a lower part of the housing **20**. The upper part of the housing **20** refers to an upper part of the housing **20** in the vertical direction **Vd**. The lower part of the housing **20** refers to a lower part of the housing **20** in the vertical direction **Vd**.

The second layer **80** is provided to conform to the outer shape of the first layer **70**. The second layer **80** includes a first segment **81** and a second segment **82**. The first segment **81** includes a first accommodating recess **81a**. The first accommodating recess **81a** opens toward the second segment **82**. The second segment **82** includes a second accommodating recess **82a**. The second accommodating recess **82a** opens toward the first segment **81**. The first accommodating recess **81a** and the second accommodating recess **82a** have shapes that conform to the outer shape of the first layer **70**.

The first segment **81** includes a first opening end face **81b**. The first opening end face **81b** is an annular flat surface and surrounds the opening of the first accommodating recess **81a**, which faces the second segment **82**. The first opening end face **81b** is a flat surface that extends in the horizontal direction. The second segment **82** includes a second opening end face **82b**. The second opening end face **82b** is an annular flat surface and surrounds the opening of the second accommodating recess **82a**, which faces the first segment **81**. The second opening end face **82b** is a flat surface that extends in the horizontal direction.

The first opening end face **81b** and the second opening end face **82b** are in contact with each other over the entire periphery. A portion in the second layer **80** at which the first

opening end face **81b** and the second opening end face **82b** are in contact with each other is a boundary **83** between the first segment **81** and the second segment **82**. The first segment **81** is disposed above the boundary **83**, that is, at a position corresponding to an upper part of the housing **20**. The second segment **82** is disposed below the boundary **83**, that is, at a position corresponding to a lower part of the housing **20**.

A direction in which the first segments **71, 81** and the second segments **72, 82** are joined to each other is defined as an up-down direction **D**. In the present embodiment, the up-down direction **D** agrees with the vertical direction **Vd**. For example, the up-down direction **D** may be slightly inclined with respect to the vertical direction **Vd**. The up-down direction **D** may be inclined with respect to the vertical direction **Vd** to such an extent that the first segments **71, 81** are located at least above the second segments **72, 82** in the vertical direction **Vd**.

As shown in FIG. 2, a length of the first segment **71** of the first layer **70** in the circumferential direction **B** is shorter than a length of the second segment **72** of the first layer **70** in the circumferential direction **B**. The size of the first segment **71** is smaller than the size of the second segment **72**. Thus, the boundary **73** between the first segment **71** and the second segment **72** is located above the axis **m** of the housing **20** in the up-down direction **D** due to the difference in size between the first segment **71** and the second segment **72**.

A length of the first segment **81** of the second layer **80** in the circumferential direction **B** is the same as a length of the second segment **82** of the second layer **80** in the circumferential direction **B**. The size of the first segment **81** is the same as the size of the second segment **82**. Thus, a boundary **83** between the first segment **81** and the second segment **82** is disposed at the same position as the axis **m** of the housing **20** in the up-down direction **D**.

<First Selection Layer, Second Selection Layer, Outermost Layer>

As shown in FIGS. 1 and 2, the layers **70, 80** form the soundproof cover **60**. The second layer **80**, which is one of the layers **70, 80**, is defined as a first selection layer **91**, and the first layer **70**, which is a layer located inward of the first selection layer **91**, is defined as a second selection layer **92**. The boundary **73** in the second selection layer **92** is located above the boundary **83** in the first selection layer **91** in the up-down direction **D**. The boundary **83** in the second layer **80**, which is the outermost layer located at the outermost position of the layers **70, 80**, is located at the lowermost position among the boundaries **73, 83** in the layers **70, 80** in the up-down direction **D**.

<Method of Installing Soundproof Cover on Motor-Driven Compressor>

As shown in FIGS. 2 and 3, a method of installing the soundproof cover **60** on the motor-driven compressor **10** includes a first step **P1**, a second step **P2**, and a third step **P3**.

As shown in FIG. 2, the first step **P1** is a step of stacking the first segment **71** of the first layer **70** and the first segment **81** of the second layer **80** together. A first intermediate **101** is formed by stacking the first segment **71** of the first layer **70** and the first segment **81** of the second layer **80** together. That is, the first step **P1** is a step of forming the first intermediate **101** by stacking the first segments **71, 81** of the layers **70, 80** together.

The first segment **71** of the first layer **70** is accommodated in the first accommodating recess **81a** of the first segment **81** of the second layer **80**. The entire first segment **71** of the first layer **70** is accommodated inside the first segment **81** of the

second layer **80**. The entire outer surface of the first segment **71** of the first layer **70** is in contact with the inner surface of the first accommodating recess **81a** of the first segment **81** of the second layer **80**. In the first intermediate **101**, the first opening end face **71b** of the first segment **71** of the first layer **70** is parallel with the first opening end face **81b** of the first segment **81** of the second layer **80**.

The second step P2 is a step of stacking the second segment **72** of the first layer **70** and the second segment **82** of the second layer **80** together. A second intermediate **102** is formed by stacking the second segment **72** of the first layer **70** and the second segment **82** of the second layer **80** together. That is, the second step P2 is a step of forming the second intermediate **102** by stacking the second segments **72, 82** of the layers **70, 80** together.

The second segment **72** of the first layer **70** is accommodated in the second accommodating recess **82a** of the second segment **82** of the second layer **80**. Part of the second segment **72** of the first layer **70** protrudes from the opening of the second segment **82** of the second layer **80**. The second opening end face **72b** of the second segment **72** of the first layer **70** protrudes outward from the second segment **82** of the second layer **80**. Part of the outer surface of the second segment **72** of the first layer **70** is in contact with the entire inner surface of the second accommodating recess **82a** of the second segment **82** of the second layer **80**. In the second intermediate **102**, the second opening end face **72b** of the second segment **72** of the first layer **70** is parallel with the second opening end face **82b** of the second segment **82** of the second layer **80**.

As shown in FIGS. 2 and 3, the third step P3 is executed after the first step P1 and the second step P2 are completed. In the third step P3, the first intermediate **101** is arranged above the housing **20**, and the second intermediate **102** is arranged below the housing **20**.

The third step P3 is a step of joining the first intermediate **101** and the second intermediate **102** to each other by bringing the first intermediate **101** and the second intermediate **102** close to each other. The first opening end face **71b** of the first intermediate **101** and the second opening end face **72b** of the second intermediate **102** are brought into contact with each other, and the first opening end face **81b** of the first intermediate **101** and the second opening end face **82b** of the second intermediate **102** are brought into contact with each other. Then, as shown in FIG. 3, the housing **20** is covered with the first intermediate **101** and the second intermediate **102**. That is, the third step P3 is a step of covering the housing **20** with the first intermediate **101** and the second intermediate **102** by joining the first intermediate **101** and the second intermediate **102** to each other.

[Operation of Present Embodiment]

Operation of the present embodiment will now be described.

In the present embodiment, when the compression unit **30** and the electric motor **40** are driven, noise is transmitted via the housing **20**. However, since the housing **20** is covered with the soundproof cover **60**, the noise of the motor-driven compressor **10** is reduced.

The boundaries **73, 83** in the layers **70, 80**, which form the soundproof cover **60**, are displaced from each other in the up-down direction D. That is, the boundaries **73, 83** in all the layers **70, 80** do not extend continuously from the housing **20** to the outside of the soundproof cover **60**. Thus, noise generated from the compression unit **30** and the electric motor **40** is unlikely to leak to the outside of the soundproof cover **60**. Therefore, the noise reduction effect of the soundproof cover **60** is unlikely to be reduced.

Also, the boundary **73** in the second selection layer **92** is located above the boundary **83** in the first selection layer **91**. For this reason, even if water reaches the boundary **83** in the second layer **80**, which is the outermost layer located at the outermost position among all the layers **70, 80** and is the first selection layer **91**, the water is unlikely to reach the boundary **73** in the second selection layer **92**. Thus, even if water enters the motor-driven compressor **10** from the outside, the water is unlikely to reach the housing **20**.

[Advantages of Present Embodiment]

The present embodiment has the following advantages.

(1-1) The boundaries **73, 83** in the layers **70, 80**, which form the soundproof cover **60**, are displaced from each other in the up-down direction D. Also, the boundary **73** in the second selection layer **92** is located above the boundary **83** in the first selection layer **91**. Therefore, it is possible to maintain the noise reduction effect of the soundproof cover **60** while preventing water from reaching the housing **20**.

(1-2) The boundary **83** in the second layer **80**, which is the outermost layer located at the outermost position among all the layers **70, 80**, is located at the lowermost position among the boundaries **73, 83** in all the layers **70, 80**. For this reason, water entering the boundary **83** in the second layer **80** is unlikely to pass through the boundary **73** in the first layer **70**, which is located inward of the second layer **80**. Therefore, water is unlikely to reach the housing **20**.

(1-3) According to the method of installing the soundproof cover **60** on the motor-driven compressor **10** of the present embodiment, the first segments **71, 81** of the respective layers **70, 80** are stacked together in advance to form the first intermediate **101**. Then, the second segments **72, 82** of the respective layers **70, 80** are stacked together in advance to form the second intermediate **102**. This configuration simplifies the final step of attaching the soundproof cover **60** to the housing **20** of the motor-driven compressor **10**.

A motor-driven compressor **10** according to a second embodiment will now be described with reference to FIG. 4. The main difference of the present embodiment from the first embodiment is that the soundproof cover **60** includes a greater number of layers. The differences will be described, and like or the same reference numerals are given to those components that are like or the same as the corresponding components of the first embodiment, and detailed explanations are omitted.

<Soundproof Cover>

As shown in FIG. 4, the soundproof cover **60** includes a third layer **110**. The third layer **110** is stacked on the second layer **80**. The third layer **110** covers the second layer **80**. The third layer **110** is provided to conform to the outer shape of the second layer **80**. The soundproof cover **60** includes multiple layers **70, 80**, and **110**, which at least include the first layer **70** and the second layer **80**.

In the present embodiment, the third layer **110** is formed of a material having high vibration damping properties, such as a closed cell rubber sheet or a semi-closed cell rubber sheet. The third layer **110** includes a first segment **111** and a second segment **112**. The first segment **111** includes a first accommodating recess **111a**. The first accommodating recess **111a** opens toward the second segment **112**. The second segment **112** includes a second accommodating recess **112a**. The second accommodating recess **112a** opens toward the first segment **111**. The first accommodating recess **111a** and the second accommodating recess **112a** have shapes that conform to the outer shape of the second layer **80**.

The first segment **111** includes a first opening end face **111b**. The first opening end face **111b** is an annular flat

surface and surrounds the opening of the first accommodating recess **111a**, which faces the second segment **112**. The first opening end face **111b** is a flat surface that extends in the horizontal direction. The second segment **112** includes a second opening end face **112b**. The second opening end face **112b** is an annular flat surface and surrounds the opening of the second accommodating recess **112a**, which faces the first segment **111**. The second opening end face **112b** is a flat surface that extends in the horizontal direction.

The first opening end face **111b** and the second opening end face **112b** are in contact with each other over the entire periphery. A portion in the third layer **110** at which the first opening end face **111b** and the second opening end face **112b** are in contact with each other is a boundary **113** between the first segment **111** and the second segment **112**. The first segment **111** is disposed above the boundary **113**, that is, at a position corresponding to an upper part of the housing **20**. The second segment **112** is disposed below the boundary **113**, that is, at a position corresponding to a lower part of the housing **20**.

A length of the first segment **111** of the third layer **110** in the circumferential direction B is greater than a length of the second segment **112** of the third layer **110** in the circumferential direction B. The size of the first segment **111** is larger than the size of the second segment **112**. Thus, the boundary **113** between the first segment **111** and the second segment **112** is located below the axis m of the housing **20** in the up-down direction D due to the difference in size between the first segment **111** and the second segment **112**.

<First Selection Layer, Second Selection Layer, Outermost Layer>

The layers **70, 80, 110** form the soundproof cover **60**. The third layer **110**, which is one of the layers **70, 80, 110**, is defined as a first selection layer **91**, and the first layer **70**, which is a layer located inward of the first selection layer **91**, is defined as a second selection layer **92**. The boundary **73** in the second selection layer **92** is located above the boundary **113** in the first selection layer **91** in the up-down direction D.

The layers **70, 80, 110** form the soundproof cover **60**. The third layer **110**, which is one of the layers **70, 80, 110**, is defined as the first selection layer **91**, and the second layer **80**, which is a layer located inward of the first selection layer **91**, is defined as the second selection layer **92**. The boundary **83** in the second selection layer **92** is located above the boundary **113** in the first selection layer **91** in the up-down direction D.

The boundary **113** of the third layer **110**, which is the outermost layer located at the outermost position among the layers **70, 80, 110**, is located at the lowermost position among the boundaries **73, 83, 113** in the layers **70, 80, 110** in the up-down direction D.

<Method of Installing Soundproof Cover on Motor-Driven Compressor>

In the method of installing the soundproof cover **60** on the motor-driven compressor **10**, the first step P1 includes an additional step of stacking the first segment **111** of the third layer **110** on the first segment **81** of the second layer **80**. A first intermediate **101** is formed by stacking the first segment **71** of the first layer **70**, the first segment **81** of the second layer **80**, and the first segment **111** of the third layer **110** together. That is, the first step P1 is a step of forming the first intermediate **101** by stacking the first segments **71, 81, 111** of the layers **70, 80, 110** together.

The second step P2 includes an additional step of stacking the second segment **112** of the third layer **110** on the second segment **82** of the second layer **80**. A second intermediate

102 is formed by stacking the second segment **72** of the first layer **70**, the second segment **82** of the second layer **80**, and the second segment **112** of the third layer **110** together. That is, the second step P2 is a step of forming the second intermediate **102** by stacking the second segments **72, 82, 112** of the layers **70, 80, 110** together.

The third step P3, which is described in the first embodiment, additionally brings the first opening end face **111b** of the first intermediate **101** and the second opening end face **112b** of the second intermediate **102** into contact with each other. That is, the third step P3 is a step of covering the housing **20** with the first intermediate **101** and the second intermediate **102** by joining the first intermediate **101** and the second intermediate **102** to each other.

[Operation of Present Embodiment]

Operation of the present embodiment will now be described.

The boundaries **73, 83, 113** in the layers **70, 80, 110**, which form the soundproof cover **60**, are displaced from each other in the up-down direction D. That is, the boundaries **73, 83, 113** in all the layers **70, 80, 110** do not linearly extend from the housing **20** to the outside of the soundproof cover **60**. Thus, noise generated from the compression unit **30** and the electric motor **40** is unlikely to leak to the outside of the soundproof cover **60**. Therefore, the noise reduction effect of the soundproof cover **60** is unlikely to be reduced.

In addition, the boundary **83** in the case in which the second layer **80** is defined as the second selection layer **92** is located above the boundary **113** in the case in which the third layer **110** is defined as the first selection layer **91**. The boundary **73** in the case in which the first layer **70** is defined as the second selection layer **92** is located above the boundary **113** in the case in which the third layer **110** is defined as the first selection layer **91**.

Therefore, even if water reaches the boundary **113** in the third layer **110**, which is the first selection layer **91**, the water is unlikely to reach the boundaries **73, 83** in the layers **70, 80**, which can be defined as the second selection layer **92**. Thus, even if water enters the motor-driven compressor **10** from the outside, the water is unlikely to reach the housing **20**.

[Advantages of Present Embodiment]

The present embodiment has the following advantages.

(2-1) The boundaries **73, 83, 113** in the layers **70, 80, 110**, which form the soundproof cover **60**, are displaced from each other in the up-down direction D. Further, the boundaries **73, 83** in the layers **70, 80**, which can be defined as the second selection layer **92**, are located above the boundary **113** in the third layer **110**, which is the first selection layer **91**. Therefore, it is possible to maintain the noise reduction effect of the soundproof cover **60** while preventing water from reaching the housing **20**.

(2-2) The boundary **113** in the third layer **110**, which is the outermost layer located at the outermost position among the layers **70, 80, 110**, is located at the lowermost position among the boundaries **73, 83, 113** in the layers **70, 80, 110**. For this reason, water entering the boundary **113** in the third layer **110** is unlikely to pass through the boundaries **73, 83** in the layer **70, 80**, which are located inward of the third layer **110**. Therefore, water is unlikely to reach the housing **20**.

[Modifications]

The above-described embodiments may be modified as follows. The above-described embodiments and the following modifications can be combined as long as the combined modifications remain technically consistent with each other.

11

In the second embodiment, the position of the boundary 113 in the third layer 110 may be changed as follows.

As shown in FIG. 5, the boundary 113 in the third layer 110 may be located between the boundary 73 in the first layer 70 and the boundary 83 in the second layer 80 in the up-down direction D. In this modification, the second layer 80 may be defined as the first selection layer 91, and the first layer 70 may be defined the second selection layer 92. Alternatively, the third layer 110 may be defined the first selection layer 91, and the first layer 70 may be defined as the second selection layer 92.

As shown in FIG. 6, the boundary 113 in the third layer 110 may be located at the same position as the boundary 83 in the second layer 80 in the up-down direction D. In this modification, the second layer 80 may be defined as the first selection layer 91, and the first layer 70 may be defined the second selection layer 92. Alternatively, the third layer 110 may be defined the first selection layer 91, and the first layer 70 may be defined as the second selection layer 92.

As shown in FIG. 7, the boundary 73 in the first layer 70 may be located at the same position as the boundary 113 in the third layer 110 in the up-down direction D, and the boundary 83 in the second layer 80 may be located above the boundaries 73, 113 in the layers 70, 110. In this modification, the third layer 110 is defined as the first selection layer 91, and the second layer 80 is defined as the second selection layer 92.

In the modification shown in FIG. 7, the boundary 113 in the third layer 110 may be located below the boundary 73 in the first layer 70. In this modification, the third layer 110 may be defined as the first selection layer 91, and the second layer 80 may be defined the second selection layer 92. Alternatively, the third layer 110 may be defined the first selection layer 91, and the first layer 70 may be defined as the second selection layer 92.

In the modification shown in FIG. 7, the boundary 73 in the first layer 70 may be located below the boundary 113 in the third layer 110. In this modification, the third layer 110 is defined as the first selection layer 91, and the second layer 80 is defined as the second selection layer 92.

In the modification shown in FIG. 7, the boundary 83 in the second layer 80 may be located below the boundaries 73, 113 in the layers 70, 110. In this modification, the second layer 80 is defined as the first selection layer 91, and the first layer 70 is defined as the second selection layer 92. In the second embodiment and the above-described modifications, the sizes of the first segment and the second segment in at least one of all the layers 70, 80, 110 may be changed.

In the first embodiment, the boundary 73 in the first layer 70 may be located below the axis m of the housing 20. In this modification, the boundary 83 in the second layer 80 is displaced to be located below the boundary 73 in the first layer 70. That is, when the second layer 80 is defined as the first selection layer 91 and the first layer 70 is defined the second selection layer 92, the boundary 73 in the second selection layer 92 may be located above the boundary 83 in the first selection layer 91.

In the above-described embodiments and modifications, the first opening end faces 71b, 81b, 111b and the second opening end faces 72b, 82b, 112b are surfaces extending in the horizontal direction, but the present disclosure is not limited to this. For example, the first opening end faces 71b, 81b, 111b and the second opening end faces 72b, 82b, 112b may each have a step in the up-down direction D. The shapes of the first opening end faces 71b, 81b, 111b and the shapes of the second opening end face 72b, 82b, 112b may be changed. Such modifications are possible as long as the

12

boundary in the second selection layer 92 is entirely located above the boundary in the first selection layer 91.

In each of the above-described embodiments, the first segment 71 and the second segment 72 may be coupled to each other by, for example, a hinge or the like. The first segment 81 and the second segment 82 may be coupled to each other by, for example, a hinge or the like. The first segment 111 and the second segment 112 may be coupled to each other by, for example, a hinge or the like.

In each of the above-described embodiments, the number of layers forming the soundproof cover 60 may be greater than three. Even in this modification, the boundary in the second selection layer 92 is arranged to be above the boundary in the first selection layer 91.

In each of the above-described embodiments, the housing 20 may include a portion that protrudes in a radial direction, which is orthogonal to the axis m of the housing 20. Further, the portion protruding from the housing 20 in a radial direction may also be covered by the soundproof cover 60.

In this modification, the size of the first segment and the size of the second segment in one of the first selection layer 91 and the second selection layer 92 are changed such that the boundary in the second selection layer 92 is located above the boundary in the first selection layer 91.

In each of the above-described embodiments, the first layer 70 may be made of a material having high sound insulating properties. The second layer 80 may be made of a material having high sound absorbing properties. In addition, the third layer 110 may be made of a material having

high sound absorbing properties or high sound insulating properties, and the first layer 70 or the second layer 80 may be made of a material having high vibration damping properties. The properties of the respective layers forming the soundproof cover 60, such as the sound absorbing

properties, the sound insulating properties, or the vibration damping properties, may be changed in each layer. The soundproof cover 60 may be made of any material as long as the material has a soundproof function. The properties of multiple layers forming the soundproof cover 60 may have

properties other than sound absorbing properties, sound insulating properties, or vibration damping properties.

In each of the above-described embodiments, the compression unit 30 is not limited to a scroll type, but may be, for example, a piston type or a vane type.

In each of the above-described embodiments, the motor-driven compressor 10 may be mounted on a fuel cell electric vehicle and use the compression unit 30 to compress air, which is a fluid supplied to the fuel cell.

Various changes in form and details may be made to the examples above without departing from the spirit and scope of the claims and their equivalents. The examples are for the sake of description only, and not for purposes of limitation. Descriptions of features in each example are to be considered as being applicable to similar features or aspects in other examples. Suitable results may be achieved if sequences are performed in a different order, and/or if components in a described system, architecture, device, or circuit are combined differently, and/or replaced or supplemented by other components or their equivalents. The scope of the disclosure is not defined by the detailed description, but by the claims and their equivalents. All variations within the scope of the claims and their equivalents are included in the disclosure.

What is claimed is:

1. A motor-driven compressor, comprising:
a compression unit that compresses a fluid;
an electric motor that drives the compression unit;

13

a housing that accommodates the compression unit and the electric motor; and
 a soundproof cover that covers the housing, wherein the soundproof cover includes a first layer and a second layer, the first layer being placed over the housing, and the second layer being placed over the first layer, the first layer having a boundary defined between two opposing segments of the first layer, wherein one of the two opposing segments of the first layer is located above the other of the two opposing segments of the first layer,
 the second layer having a boundary defined between two opposing segments of the second layer, wherein one of the two opposing segments of the second layer is located above the other of the two opposing segments of the second layer,
 the boundary of the first layer is located above the boundary of the second layer.
 2. The motor-driven compressor according to claim 1, further comprising:
 an outermost layer having a boundary defined between two opposing segments of the outermost layer, the outermost layer being placed over the second layer, and
 the boundary of the outermost layer is located at a position lower than both the boundary of the first layer and the boundary of the second layer.
 3. The motor-driven compressor according to claim 1, wherein the first layer and the second layer are among a plurality of layers and the second layer is an outermost layer, and
 the boundary of the second layer is located at a position lower than each boundary of the plurality of layers.

14

4. A method of installing a soundproof cover on a motor-driven compressor, the method comprising:
 providing a first layer having two opposing segments, providing a second layer having two opposing segments, wherein
 the first layer and the second layer form the soundproof cover, the soundproof cover covering a housing of the motor-driven compressor, the first layer being placed over the housing, and the second layer being placed over the first layer; the first layer having a boundary defined between the two opposing segments of the first layer, wherein one of the two opposing segments of the first layer is located above the other of the two opposing segments of the first layer,
 the second layer having a boundary defined between the two opposing segments of the second layer, wherein one of the two opposing segments of the second layer is located above the other of the two opposing segments of the second layer,
 the boundary of the first layer is located above the boundary of the second layer;
 forming a first intermediate by stacking the other of the two opposing segments of the first layer and the other of the two opposing segments of the second layer together;
 forming a second intermediate by stacking the one of the two opposing segments of the first layer and the one of the two opposing segments of the second layer together; and
 covering the housing with the first intermediate and the second intermediate by joining the first intermediate and the second intermediate to each other.
